UNITED STATES PATENT OFFICE.

HYMAN E. COHEN, OF NEW YORK, N. Y., ASSIGNOR TO UNITED STATES HOFFMAN MACHINERY CORPORATION, OF NEW YORK, N. Y., A CORPORATION OF DELAWARE

PRESSING MACHINE.

Application filed January 2, 1923. Serial No. 610,259.

To all whom it may concern:

Be it known that I, HYMAN E. COHEN, a citizen of the United States, residing at New York, in the county of Queens and State of New York, have invented certain new and useful Improvements in Pressing Machines, of which the following is a specification.

This invention pertains to garment presses and more particularly to the control mechanism in that type wherein an initial relatively light pressure between the pressing elements is effected followed by a heavy pressure, which latter effectually flattens the seams, edges, or the like of the garment being operated upon. In machines of this type the initial pressure between the pressing elements is usually effected through the actuation of a pedal by the operator and the final heavy pressure through the agency of a power mechanism operated by an electric motor.

The main object of the present invention is to provide means under the control of the operator whereby the initiation, duration and release of the heavy pressure may be controlled as may be found desirable. Ordinarily in presses of the type above referred to it has been the usual practice to effect the application and release of the heavy pressure through the use of a special automatically operated switch or commutator operating in timed relation with other portions of the mechanism, whereas in the instant case the control is such that the initiation, duration and release of the final heavy pressure is directly under the control of the operator.

The invention is illustrated in connection with a press of a type well known in the art, wherein,—

Fig. 1 is a side elevation of the press with the parts in such position that final heavy pressure is being applied;

Fig. 2 a rear elevation of a portion of the main frame, the power applying means, and the switch control mechanism;

Fig. 3 a horizontal sectional view taken on the line 3—3 of Fig. 4; and

Figs. 4 and 5 elevations of the switch and its control means illustrating the parts in two different positions.

The press shown is substantially the same as that set forth and claimed in Letters Patent No. 1,426,120, dated August 15, 1922, to

Spencer and Geldhof, to which reference is made. It comprises a rigid frame 1 carrying at its forward upper portion a buck 2 with which cooperates a head 3. Said head is attached to the forward end of a lever 4 fulcrumed at 5 in the main frame. A toggle, comprising links 6 and 7, is employed to rock the lever to bring the head into pressing relation to the buck, the upper end of link 6 being pivotally connected to lever 4 adjacent its rear end, a compensating spring 8 being employed as is usual. The lower end of toggle link 7 is pivotally connected at 9 to a lever 10 fulcrumed at 11 to the main frame 1.

To close the press, a second toggle, comprising a pair of links 12 and 13, is employed, link 12 being pivotally connected to link 7 while the forward end of link 13 is pivotally attached at 14 to the frame 1. A link 15 attached to link 13 extends downwardly therefrom and is pivotally connected to a foot lever 16 fulcrumed upon a power shaft 17 mounted in suitable bearings in frame 1. The forward end of lever 10 is bifurcated and straddles a cam 18 secured to the power shaft. Motion is imparted to the power shaft and consequently to cam 18 through a gear 19 secured to the shaft. A pinion 20 meshes with the gear, said pinion being secured to a shaft 21 which likewise carries a worm gear 22, the latter being in mesh with a worm 23 driven by an electric motor 24.

Secured to the main frame 1 is a switch box 25 in which is mounted a switch arm 25^a, Fig. 3, adapted to close the circuit to the motor when the switch is in its uppermost or its lowermost position. Suitable leads, shown in Fig. 1, extend from the switch to the motor. The contact arm of the switch is secured to a shaft 26 journaled in the switch box body and an arm or lever 27 is affixed to the outer end thereof. Suitable stops, as 28 and 29, limit the movement of said lever 27 in its upward and downward movements or when the lever reaches such position that the circuit is closed through the switch arm. Mounted for vertical reciprocation in a pair of lugs or brackets 30 and 31, is a rod 32, having secured thereto a collar 33. A coil spring 34 has one end attached to said collar and its opposite end to a pin or stud 35 extending outwardly from the lever 27. To the lower end of the

rod 32 there is pivotally connected a pitman or rod 36, which in turn is secured to a wrist pin 37 extending outwardly from a disk 38 secured to and rotatable with the shaft 17. As above noted, this shaft is rotated through the gearing interposed between it and the motor 24. The switch box 25 carries a two-armed bracket 39, in which is slidably supported one end of a stop rod 40, a spring 41 coacting with a collar 42 secured to the rod, serving to move the rod endwise and project its inner end into the path of the lever or arm 27, for a purpose which will presently appear. The outer end of the rod 40 is pivotally connected to a hand lever 43 fulcrumed at its upper end to a bracket 44 secured to the under face of the table 45 of the machine.

In the use of the machine, the goods to be pressed having been placed upon the buck 2, the head is lowered through the operator grasping a handle 46 secured to the head, and drawing the same downwardly. Pressure is then applied to the outer end of the lever 16, which, acting through the link 15, draws the toggle links 12 and 13 down into the position shown in Fig. 1, thereby exerting an outward thrust against the member 7 of the main toggle, and applying pressure through the straightening of such toggle through the lever 4 to the head 3. This effects a moderate degree of pressure. If it then be desired to exert a heavy pressure, the operator will grasp the handle 43 and draw the stop rod 40 outwardly, releasing its inner end from contact with the arm 27, permitting the arm 27 to be thrown downwardly through the agency of the spring 34, from the full line position, Fig. 4, to the dotted line position. The cam 18 is at such time in its lowest position and the rod 36 is likewise in its lowest position. The arm 27, as it swings downwardly through the action of the spring, carries the switch arms into operative relation with the lower pair of terminals in the switch box and current is permitted to flow to the motor 24, starting the same, and through the gearing, as above described, causing a rotation of the shaft 17 and the cam carried thereby. As the cam rotates it rocks the lever 10 upon its fulcrum 11, the lever being moved upwardly and, as a consequence, exerting a thrust upon the then straightened main toggle comprising the elements 6 and 7. Rotation of the shaft 17 imparts motion to the disk 38 and as a consequence the rod 36 is moved from the position shown in Fig. 4 to the position shown in Figs. 1 and 5. The spring 34 will then move from the position shown in Fig. 4 to the position shown in Figs. 1 and 5, and will have a tendency to draw the arm 27 upwardly and break the switch and consequently interrupt the current. If the stop rod 40 is allowed to stand in its innermost position through the action of the spring 41, the lever 27 will contact the inner end of the stop rod 40 and will be held in the position shown in Fig. 5. Consequently the current flow will be interrupted and the motor come to rest, leaving the heavy pressure mechanism in that position where it will continue to exert such heavy pressure. This position may be maintained as long as desired, and when the heavy pressure is to be released, the operator need only draw the lever 43 outwardly and immediately the spring 34 will snap the arm 27 upwardly against the fixed stop 28 and again restore the current to the circuit and to the motor through the upper switch terminals. The parts would then be in the position shown in Fig. 1 and operation of the motor would rotate the cam 18 and as a consequence move the lever 10 downwardly and relieve the parts from the heavy pressure which had been previously exerted thereon. If it be desired to only have the heavy pressure momentarily exerted, all that is necessary to do is to have the operator hold the stop rod 40 out of the path of movement of the arm 27 so that it will pass from the dotted line position, Fig. 4, where the current is on and the motor is operating, to effect final pressure, to the uppermost position shown in Fig. 1, which will effect a continuous operation of the motor until such time as the cam has made a complete cycle. In other words, the rod 36 will pass from the position shown in Fig. 4 upwardly to the position shown in Fig. 1, and back again to the position shown in Fig. 4, the current being interrupted at this time by the withdrawal of the switch blades from the switch terminals and the arm coming to rest upon the inner end of the stop rod 40 which has been in the meantime allowed to move inwardly.

What is claimed is,—

1. In a pressing machine the combination of relatively movable cooperating pressing elements; operator actuated means for bringing said elements into pressing relation; power actuated means for effecting a final heavy pressure between said elements; an electric motor for actuating said means; a switch controlling the motor circuit; means actuated by the power actuated means for opening and closing the switch; and a stop under the control of the operator acting to normally arrest the switch in its open position.
2. In a pressing machine the combination of relatively movable cooperating pressing elements; operator actuated means for bringing said elements into pressing relation; power actuated means for effecting a final heavy pressure between said elements; an electric motor for actuating said means; a double throw switch controlling the motor circuit; means actuated by

the power actuated means for opening and closing the switch; and a stop under the control of the operator acting to normally arrest the switch in its open position.

5. 3. In a pressing machine, the combination of relatively movable cooperating pressing elements; means for bringing said elements into pressing relation; means including an electric motor acting through 60
10 said aforesaid means to effect a relatively heavy pressure between said pressing elements; a switch controlling the motor circuit; means actuated by the heavy pressure effecting means tending to close the switch; 65
15 and a stop under the control of the operator normally acting to hold the switch in its open position.

4. In a pressing machine, the combination of relatively movable cooperating 20
20 pressing elements; operator actuated means for bringing said elements into pressing relation; a cam serving when moved to effect through said operator actuated means a heavy pressure between said pressing elements; an electric motor for actuating said cam; a switch for controlling the motor circuit; means movable in timed relation with the cam serving to close the switch; and a 25
30 releasable stop under the control of the operator normally serving to hold the switch in its open position.

5. In a pressing machine, the combination of relatively movable cooperating 35
35 pressing elements; operator actuated means for bringing said elements into pressing relation; power actuated means including an electric motor for effecting a subsequent heavy pressure; a switch controlling the motor circuit; means associated with said 40
40 power means acting to close the switch both when the power means is in its release position and in its heavy pressure position; and a stop under the control of the operator normally acting to hold the switch open.

45. 6. In a pressing machine, the combina-

tion of relatively movable cooperating pressing elements; operator actuated means for bringing said elements into pressing relation; power actuated means including an electric motor for effecting a subsequent 60
60 heavy pressure; a switch controlling the motor circuit; means associated with said power means acting to close the switch both when the power means is in its release position and in its heavy pressure position; an 65
65 arm connected to the switch and movable therewith; a rod, one end of which normally stands in the path of movement of said arm; and means, under the control of the operator for moving the rod out of arresting relation to the arm.

7. In a pressing machine, the combination of relatively movable cooperating pressing elements; operator actuated means for bringing said elements into pressing relation; power actuated means including an electric motor for effecting a subsequent heavy pressure; a switch controlling the motor circuit; means associated with said power means acting to close the switch 70
70 both when the power means is in its release position and in its heavy pressure position; an arm connected to the switch and movable therewith; and means, under the control of the operator, for normally 75
75 arresting the movement of said arm and holding the switch open.

8. In a power operated mechanism, the combination of a movable element; power actuated means, including an electric motor, 80
80 for actuating said element; a switch serving to control the flow of current to the motor; means cooperating with the power mechanism for moving the switch; and operator controlled means for arresting the 85
85 switch and holding it in its open position.

In testimony whereof I have signed my name to this specification.

HYMAN E. COHEN.
